UNITED STATES PATENT OFFICE.

DAVID C. KLAUSMEYER, OF CINCINNATI, OHIO, ASSIGNOR TO THE CINCINNATI BICK-FORD TOOL COMPANY, OF CINCINNATI, OHIO, A CORPORATION OF OHIO.

GENERAL SAFETY INTERLOCK.

Application filed April 9, 1923. Serial No. 631,008.

To all whom it may concern:

Be it known that I, DAVID C. KLAUSMEYER, a citizen of the United States, and residing at Cincinnati, in the county of Hamilton and State of Ohio, have invented a new and Improved General Safety Interlock, of which the following specification is a full disclosure.

This invention relates to metal-planing machines, and has for its primary objective the provision of a general safety interlock to control the operation of adjusting the sliding cross-head which carries the tools, upon the stanchions which rise from the bed 15 above the moving table that supports the work in position for treatment.

In planing-machines for heavy service, this overhead structure is of a massive character, and it is customary to provide mechanism for elevating the heavy cross-head by power devices, in order to effect its sliding adjustment as rapidly as possible, and such power-operated adjusting-mechanism usually embodies speed-changing and controlling-devices operable manually to cause the power-actuated adjusting-mechanism to act at the desired speed, and to shift it into a neutral position when the adjustment has been effected.

Means are also utilized customarily to clamp the cross-head in adjusted position upon its slideways on the stanchions, and the character of the clamping means has been such, in the conventional design of planing-machines, that the operator not infrequently fails to release the clamping means before throwing the power-actuated adjusting-mechanism for the cross-head into action, so that the powerful adjusting action is resisted by the clamping-means, with resultant disaster to either or both of these instrumentalities.

In accordance with the present invention, a general safety interlock is provided by which clamping-devices of a special character are provided, in such numbers, and so situated, as to insure absolute rigidity of the cross-head, and these clamping-devices are so co-ordinated with controlling devices for the power-actuated adjusting-mechanism that it is impossible for the operator, by inadvertence or design, to start the adjustment of the cross-head, either manually or by the power mechanism, until he has released each

of the clamping-devices, and conversely, by 55 the novel construction and arrangement of this general safety interlock it is rendered impossible to clamp the cross-head to the stanchions while the power-actuated adjusting-mechanism is in position for action. If 60 by inadvertence the controlling-devices for the power-adjustment should be left in position for action when the power is shut off, the clamping-devices will automatically have been released by the general safety 65 interlocking arrangements, thus avoiding disaster, for there will be no clash of power action against clamping action and the movement of the cross-head will give immediate notice to the operator, upon start 70 of the power, that he must operate the clamps, and consequently set the power controlling devices in neutral position, if he does not desire the adjustive action to continue.

Another objective of this invention is to provide a duplex interlocking-system with controlling-devices of a type devised to give an unmistakable visual warning of the status of the system at any given moment, and situated on the cross-head, adjacent to the working stations of the operator on each side, for convenience of operation, with connections running thence to centralized power-controlling devices overhead, out of 80 the way of the operator, and in convenient position for application and distribution of the power, through the conventional transmission, to the cross-head.

In planing-machines, the working stations are widely separated, by the structure, and the manually-operated controlling devices on one side are inaccessible to the operator when working at the other side, so that the provision of a duplex system of control, 90 having members at each of these working stations, and co-ordinated so that the power-operated adjusting devices can only be thrown into action when the clamping 95 means on both sides have been thrown out of action, is an improvement of notable importance.

Still another objective of this invention is to provide means for automatic operation of the general safety interlock when the cross-head reaches either the upper or the lower limit of its traverse, so that if, by inadvertence of the operator, or some acci-

dent which prevents proper attention by him, or by unauthorized or accidental starting of the power-operated adjusting-mechanism in his absence, the cross-head is caused 5 to approach the danger point at either end of its traverse, the controlling-devices will be actuated automatically and will set in neutral position a power-control-element, which in accordance with this invention 10 constitutes the central member of the general safety interlock, thus bringing the cross-head to rest in a safe position.

Other objects and advantages will be in 15 part indicated in the following description 15 and in part rendered apparent therefrom in connection with the annexed drawings.

To enable others skilled in the art so 20 fully to apprehend the underlying features hereof that they may embody the same in 20 the various ways contemplated by this invention, drawings depicting a preferred typical construction have been annexed as 25 a part of this disclosure and, in such drawings, like characters of reference denote corresponding parts throughout all the views, of which:—

Fig. 1 is a view in rear elevation of a 30 planing-machine in the construction of which this invention has been embodied. Fig. 2 is a plan view of the same. Fig. 3 is a view in side elevation thereof, with parts 35 broken away. Fig. 4 is a horizontal sectional view on the line 4—4 of Fig. 3, and Fig. 5 is a view similar to Fig. 3 but on a 40 smaller scale, so that this figure illustrates completely one of the stanchions with its associated parts. In the drawings, the parts designated by the reference characters 1 and 2 are the stanchions of a planing-machine, which with the overhead bridge 3 constitute 45 the supporting structure usual in the conventional planing-machines of this type, the stanchions being formed with ways 5 upon which is mounted slidably a cross-head 6 which serves as an adjustable support for 50 the tools that are to operate upon articles carried upon the work-table B of the planing-machine.

For the elevational adjustment of the 55 cross-head 6, suitable means are provided, such as the conventional vertical lead-screws 7, mounted rotatably in suitable bearings in the bridge 3 and extending down through the cross-head, one on each side of the machine. These lead-screws have at their upper ends bevel-gears 8 in mesh with bevel-gears 9 upon a shaft 10 which is carried 60 rotatably in bearings 11 upon the bridge 3. This shaft may have a squared end as indicated at 12 to receive a crank by which it may be operated manually, and provision is made for operating it by power at different rates of speed, forward and reverse, through the medium of a clutch-member 13 shiftable 65 on the shaft 10 into engagement with clutch-

members 14 and 15, alternatively, these gears being in mesh with suitable driving-gears 16 and 17 of different sizes fast upon a shaft 18 rotatably mounted in bearings 19 supported by a casing 20 mounted on the bridge 3, the shaft 18 being hereinafter designated the primary shaft, while the shaft 10 is designated as the secondary shaft, for the sake of brevity. A reversing gear (see Fig. 3) is preferably provided as indicated at 150, 70 carried by a shaft 151, mounted in suitable bearings in the casing 20, these bearings not being shown, as they may be, and preferably are, of conventional structure. The power may be applied from any suitable source 80 through the medium of a pulley 21 fast on the shaft 18, and suitable means are provided in accordance with this invention to serve as a central power-control-element, which takes the form in the instance illustrated of a fork 22 engaged with the clutch-member 13, from which it extends into position to be operated by a rod 23 mounted in bearings 24 upon the bridge 3.

This rod can be caused by any suitable 90 means to move axially toward the right or left, to shift the clutch into low or high gear, forward or reverse, or into the neutral position illustrated in Fig. 1, and as one suitable form of construction for so 95 moving the rod 23, there is shown at each side of the supporting structure a vertical controlling member consisting of rock-shafts 25 and 26 rotatable in the bearings 24 and connected by levers 27 and 28 with 100 the rod 23, which serves as a link to co-ordinate the movement of the rock-shafts 25 and 26. Pin-and-slot connections 23^x, between the levers 27 and 28 and the rod 23, permit the levers to move in an arcuate path 105 while the rod 23 is moved in a straight line through the bearings 24.

These rock-shafts are shown as having square portions 29 and 30 extending past the cross-head 6 and are provided with 110 bearings 31 at their lower ends, these bearings being mounted upon the stanchions, and to permit manual operation of the controlling shafts 25 and 26, they are shown as provided with handles 32 and 33, by which 115 they may be rocked in their bearings. In accordance with an important objective of this invention, provision is made for a general safety interlock constructed and arranged to co-ordinate the operation of the 120 means above described for elevational adjustment of the cross-head with means for clamping the cross-head in adjusted position, and to carry this provision into effect, any suitable means may be utilized, including a suitable form of device for clamping the cross-head 6 upon the ways 5 so as to secure the cross-head to the stanchions 1 and 2.

As the preferred form of clamp for use 125

as a part of this general safety interlock, the drawings show quadruplex handles 34, 35, 36 and 37, mounted respectively in pairs, one pair at each side of the cross-head 6, and as these hand-operated clamping devices may, and preferably will, be of similar structure, a description will suffice of the hand-lever 34, with especial reference to Fig. 4 which shows the lever and its associated parts in a horizontal sectional view.

The lever 34 cooperates with a bolt 37, passing through the cross-head 6, with a nut 38 mounted adjustably on its outer end, while the inner end 137 of the bolt is threaded and enters a threaded socket 134 formed in the head 135 of the hand-lever 34.

The bolt 37 also passes through a clamping plate 39 and when the hand-lever 34 is raised into the position shown in the drawings respectively, its action is to draw the bolt 37 and nut 38 inward, clamping the cross-head 6 and clamping-plate 39 toward each other into engagement with the slideway 5 upon which the cross-head 6 slides, locking the cross-head against sliding movement. A friction-washer 40 may be provided between the head of the hand-lever and the plate 39 and it is desirable to provide means for preventing rotation of the bolt 37, such for example as a pin 41 entering the bolt 37 and engaged with the walls of a recess 42 in the clamping-plate 39.

When the cross-head 6 is thus clamped in position by action of the hand-levers 34, 35, 36 and 37, working as above described, in each instance, it is desirable that the lead-screws 7 and their power-actuated means herebefore described, should be rendered inoperative, and any suitable structure may be utilized for that purpose.

As the preferred form of means for preventing such operation, the heads of the hand-levers are shown as provided with portions 43 and 44 which are so arranged as to embrace the squared portion 29 of the rock-shaft 25, or the squared portion 30 of the rock-shaft 26, as the case may be, in the manner shown in Fig. 4, so that the rock-shafts cannot be turned while so embraced. Likewise, after the levers 34, 35, 36 and 37 have been released, a partial rotation of the shafts 25 and 26, to shift the clutch member 13 into engagement with either of the clutch members 14 or 15, positions the squared portions 29 and 30 angularly with respect to the portions 43 and 44 of the hand-levers and thereby prevents turning of the hand-levers into locking position until the clutch member has again been shifted into its neutral position.

This position of the rock-shafts 25 and 26, in which they are held by the clamping handles against rocking movement, can only be attained when the power-control-element 22 is in its neutral position shown in Figs. 1

and 2, with the clutch-member 13 out of engagement with the clutch-gears 14 and 15, the link 23 serving to co-ordinate the movements of the rock-shafts so that when one is in position to permit clamping action, the other will be in similar position.

When the parts are in this position, each of the levers 34, 35, 36 and 37 acts as a visual signal of its interlocking status, and accordingly if the operator throws one of the levers, he not only cannot operate either of the handles 32 or 33 to throw the clutch 13 into gear but the position of the other handles will indicate to him that he must still throw any one of them which remains in the elevated position shown in the drawings.

When all of the clamps have been released by downward movement of their respective handles, both of the rock-shafts 25 and 26 will also have been released by withdrawal of the lever projections 43 and 44, and the operator can then move either the handle 32 or the handle 33 to shift the clutch-member 13 into action to produce low speed or high speed, and upward or downward adjustive movement of the cross-head 6 through the action of the lead-screws 7.

The extent of movement of the hand-levers 34, 35, 36 and 37 may be limited by adjustable set screws 46, which engage with abutments 47 in a manner readily understood.

In accordance with another important objective of this invention, means are provided acting when the cross-head 6 approaches the limits of its adjustive movement, to prevent accidental overrunning thereof, and for this purpose any suitable form of structure may be utilized.

As one convenient form, the drawings show screws 48, set respectively into brackets 49 upon the clamping-plate 39, projecting in position to be engaged with cam-shoulders 50 and 51 situated respectively at the upper and lower ends of the rock-shaft 25, so that when the cross-head 6 moves upward, the screw 48 will eventually engage the shoulder 50, and rotate the shaft 25 sufficiently to move the rod 23 and power-control-element 22 until the clutch-member 13 occupies its neutral position, when the adjustive movement will cease automatically. A similar effect is produced when the cross-head moves downward and brings its lower screw 48 into engagement with the cam shoulder 51 upon the lower end of rock-shaft 25.

It will thus be seen that this invention provides a general safety interlock which is so co-ordinated with a central control of the power-actuated adjusting mechanism for the cross-head, that the operator can operate the controlling devices from widely separated working stations upon each side of

the machine, but it is impossible for the operator, by inadvertence or design to start the adjustment of the cross-head, either manually or by the power mechanism, until 5 he has released each of the clamping devices, and conversely, by the novel construction and arrangement of this general safety interlock it is rendered impossible to clamp the cross-head of the stanchions while the 10 power-actuated adjusting mechanism is in position for action. Accordingly, there will be no clash of power action against clamping 15 action.

Without further analysis, the foregoing 15 will so fully reveal the gist of this invention that others can, by applying current knowledge, readily adapt it for various utilizations by retaining one or more of the 20 essential characteristics of either the generic or specific aspects of this invention, and, therefore, such adaptations should be, and are intended to be, comprehended within the meaning and range of equivalency of 25 the following claims.

25 Having thus revealed this invention, I claim as new and desire to secure the following combinations and elements, or equivalents thereof, by Letters Patent of the United States:

30 1. In a metal-planing machine, a supporting structure, a cross-head mounted slidingly thereon, adjusting devices to elevate said cross-head, means to actuate said adjusting devices, and clamping-means to secure said 35 cross-head to said supporting structure in adjusted position, combined with a general safety interlock co-ordinating the operation of said adjusting devices and clamping-means substantially in the manner and for 40 the purpose set forth, said safety interlock embodying a plurality of controlling devices operable manually from a plurality of widely separated stations one on each side of said planing-machine.

45 2. In a metal-planing machine, a supporting structure, a cross-head mounted slidingly thereon, duplex adjusting devices to elevate said cross-head, a central power-operated means to actuate said adjusting devices, and 50 duplex clamping-means to secure said cross-head to said supporting structure in adjusted position, combined with a general safety interlock co-ordinating the operation of said adjusting devices and clamping-means substantially in the manner and for the purpose 55 set forth.

60 3. In a metal-planing machine, a supporting structure, a cross-head mounted slidingly thereon, adjusting devices to elevate said cross-head, power-operated means to actuate said adjusting-devices, clamping-means to secure said cross-head to said structure in adjusted position, and controlling devices for said power-operated means, combined with a 65 general safety interlock co-ordinating the

operation of said controlling devices and clamping-means substantially in the manner and for the purpose set forth.

4. In a metal-planing machine, a supporting-structure comprising stanchions, a bridge-member, and a sliding cross-head; a primary-shaft, a secondary shaft and speed-changing mechanism, including a power-control-element, all mounted on said bridge-member; duplex lead-screws geared to said secondary-shaft and said cross-head for elevational adjustment of the latter, duplex rock-shafts connected operatively with each other and with said power-control element, and provided each with a manually-operable device by which they may be rocked simultaneously to shift said power-control-element; and duplex hand-lever-clamps movable with said cross-head and serving to secure the latter to said stanchions at times, said hand-lever-clamps and rock-shafts being so constructed and arranged, relatively to each other, as to constitute a general safety interlock, operating substantially as described. 90

5. In a metal-planing machine, a supporting-structure comprising stanchions, a bridge-member, and a sliding cross-head; a primary-shaft, a secondary shaft and speed-changing mechanism, including a power-control-element, all mounted on said bridge-member; duplex lead-screws geared to said secondary-shaft and said cross-head for elevational adjustment of the latter; duplex rock-shafts connected operatively with each other and with said power-control element, and provided each with a manually-operable device by which they may be rocked simultaneously to shift said power-control-element; and quadruplex hand-lever-clamps movable with said cross-head and serving to secure the latter to said stanchions, at times, said hand-lever-clamps and rock-shafts being so constructed and arranged, relatively to each other, as to constitute a general safety interlock, operating substantially as described with said hand-levers acting at all times as visual signals, respectively, of the interlocking status. 110

6. In a metal-planing machine, a supporting structure, comprising stanchions, a cross-head mounted slidingly thereon, adjusting devices to elevate said cross-head, power-operated means to actuate said adjusting devices, and devices to secure said cross-head to said stanchions in adjusted position; combined with a general safety interlock co-ordinating the operation of said adjusting devices and clamping-devices, said interlock comprising rock-shafts connected for simultaneous rotation by a link provided with a power-control element, devices to operate said rock-shafts manually, and locking-means on said clamping-devices serving for engagement with said 125 130

rock-shafts to prevent clamping action except when said power-control element is in neutral position, said locking means serving also to prevent rocking of said shafts to shift said power-control element into position for adjustive action upon said cross-head when the latter is clamped to said stanchions.

7. In a metal-planing machine, a supporting structure, comprising stanchions and a bridge-member, combined with a cross-head mounted slidingly on ways formed upon said stanchions; duplex adjusting devices, comprising lead-screws connected with, and rotatable to elevate, said cross-head; a power-operated shaft on said bridge, geared to actuate said adjusting screws; quadruplex clamping-means, comprising bolts with hand-levers, mounted on, and operable to secure, said cross-head to said stanchions in adjusted position; and in combination therewith, a general safety interlock co-ordinating the operation of said adjusting devices and clamping-means, said interlock comprising duplex rock-shafts extending along said stanchions respectively past said cross-head adjacent to said hand-levers, and connected overhead, for co-rotation, by a link having a power-control element, each of said rock-shafts having manually operable means by which they may be rocked simultaneously to shift said power-control element into high-speed, low speed and neutral positions, and said interlock comprising also a structure and relative arrangement of said

rock-shafts and clamp-hand-levers such that when set to clamp said cross-head to said stanchions, a portion of each of said hand-levers will act to prevent rocking of said shafts, and so that each hand-lever must relax its bolt before said power element can be shifted from neutral position, and conversely none of said hand-levers can be operated to set its bolt, for clamping said cross-head, while said power-control element is set for movement of said adjusting devices.

8. In a metal-planing machine, a supporting structure, a cross-head mounted slidingly thereon, adjusting devices to elevate said cross-head, power-operated means to actuate said adjusting devices, and clamping-means to secure said cross-head to said supporting structure in adjusted position, combined with a general safety interlock co-ordinating the operation of said adjusting devices and clamping-means substantially in the manner and for the purpose set forth, said general safety interlock embodying means acting automatically, when said cross-head approaches either limit of its traverse, to render inoperative said power-operated adjusting devices.

In witness whereof, I hereunto subscribe my name, as attested by the two subscribing witnesses.

DAVID C. KLAUSMEYER.
